HOSPITAL CORRIDOR LIGHT

Frederic Lewis Garrigues, Meriden, Conn., assignor, by mesne assignments, to Connecticut Telephone & Electric Corporation, Meriden, Conn., a corporation of Delaware

Application June 12, 1928, Serial No. 284,863

4 Claims. (Cl. 177—329)

This invention relates to signal lights adapted primarily for use in hospital corridors.

An object of the invention is to provide a signal means, preferably including a plurality of lights which when one is rendered inoperative will still give a signal and will also indicate that replacement of the inoperative part is required.

Another object of the invention is to provide a signaling mechanism adapted to remain operative when a part has been damaged or destroyed and which will also indicate that a part has become inoperative.

Another object of the present invention is to provide a signal light having a plurality of separated lights which can be seen from the side as well as from the front.

One feature which is advantageous is that the lights are separated by an opaque barrier, the barrier and lights being enclosed within a suitable translucent cover so that if one of the bulbs becomes burnt out a signal will still be given, but it will be evident that a bulb requires replacement.

Another object is to provide an opaque barrier adjustable on the support so that it may be fitted snugly to translucent covers and rims of varying size.

Another object of importance is that the lights are supported in sockets mounted upon the rear face of a support, the lights being inserted in their sockets from the front of the support and extending through suitably formed openings therein, and disposed on opposite sides of a suitably vertically disposed opaque barrier plate.

Another feature of importance is that the opaque barrier disposed between the lights is attached to the front face of the support and has its outer edge closely conforming to the inside surface of the translucent cover so that the light of each bulb will be restricted to one side of the barrier.

It has been the practice in signal installation, particularly in hospitals, to provide a button at the patient's bedside which when depressed will operate a small light in the corridor advising an attendant that a signal has been given. Should the light fail to operate no signal would be given and there would be nothing to indicate that the signaling means were out of order. The present invention therefore includes a signaling device having preferably two light bulbs, each illuminating when lighted different portions of a corridor light preferably formed as a translucent dome. With both bulbs operating properly the entire translucent dome will be fully illuminated. With

but one bulb operating a portion only of the translucent dome will be illuminated indicating at once that a signal has been given, but that a light bulb requires replacement.

With these and other objects in view, my invention consists in the features of construction and operation set forth in the following specification and illustrated in the accompanying drawing.

In the accompanying drawing annexed hereto and forming a part of this specification, I have shown my invention embodied in a preferred form of hospital corridor light, but it will be understood that the invention can be otherwise embodied, and that the drawing is not to be construed as defining or limiting the scope of the invention, the claims appended to this specification being relied upon for that purpose.

In the drawing—

Fig. 1 is a front elevation of a complete hospital signal light, a part of the cover being broken away to more clearly show the construction;

Fig. 2 is a transverse sectional view taken upon the plane of line 2—2 of Fig. 1;

Fig. 3 is a typical controlling circuit for operating the signal light forming the present invention when associated with supplemental signaling means; and

Fig. 4 is a separate view of one form of barrier and means to attach it to the support.

In the above mentioned drawing, I have shown but one embodiment of the invention which is now deemed preferable, but it is to be understood that changes and modifications may be made within the scope of the appended claims without departing from the spirit of the invention.

Briefly, and in its preferred aspect, my invention may include a supporting plate to which are fastened light sockets having lights mounted therein extending through suitable openings in the plate; a barrier plate attached to the plate and disposed between the lights in the sockets; and a translucent arched or dome-shaped cover attached to the supporting plate so that a complete self-contained signal unit is provided.

Referring more in detail to the figures of the drawing, I show a supporting plate 10 of metal or other suitable material preferably beveled along its edges to fit closely against a wall. Mounted upon the rear surface of this supporting plate are light sockets 11, two individual sockets of any preferred form being shown attached to the plate 10 by screws 12 extending into posts 13 on the sockets 11. Inserted in the for-

ward ends of these sockets are light bulbs 14 preferably of different colors, such as white and red. Preferably these lights 14 are insertable into the sockets 11 from the front of the plate 10 5 through suitable openings 15 provided therefor.

Attached to the front face of the supporting plate 10 by suitable rivets or screws 16 is a barrier plate 17, preferably of metal or other opaque material separating the lights 14, one light 14 10 being on each side thereof. With the signal light in the position shown the barrier plate 17 is disposed in a vertical plane. Also mounted on the front surface of the supporting plate 10 is a hinged ring 18, a catch 19 being provided to retain it in position against the plate 10. A translucent dome-shaped member 20 is attached about its periphery to the ring 18. As shown in Fig. 2, the opaque barrier plate 17 has its free or outer edge closely adjacent the inside surface of the translucent dome 20 which in the preferred embodiment is concave. 15

In order to fit the translucent cover 20 more closely the barrier 17 may be made as shown in Fig. 4. A bracket or angle member 9 has an up-standing flange and oppositely disposed feet at opposite ends attached to the support 10 in the same manner as the barrier 17 shown in Fig. 1. To this angle member 9 the curved barrier 17 is attached by suitable screws 8. The holes in the barrier 17 and in the angle member 9 through which the screws 8 pass are made somewhat larger than the shanks of the screws 8 so that the barrier 17 may be adjusted within limits relative to its angle member 9. By this adjustment for the barrier 17 it may be properly fitted to translucent domes 20 which may vary somewhat from standard or predetermined size. 30

By this dome-like and partition construction I form separate chambers for the different lights and on account of the dome-like or arched form of the cover glass the different lights can be seen from the sides as well as from the front. 40

In Fig. 3 is shown a typical controlling circuit for operating the signal lights of the present invention when associated with a buzzer 21 and supplemental light signals 22 and 23. The circuit for each signal is separated and independent so that on injury to one signal the circuit will still operate one or more of the other signals. As shown in this figure, the two lights 14 45 preferably of different color are mounted in multiple in a circuit, the circuit being made by depressing a button 24 which engages flexible fingers 25 and 26 with a conductor ring 27 on the button 24. The supplemental light 22 in another 50 circuit is operated by the same source of current, but including a different flexible finger 28 operated by the same button. The second supplemental light signal is operated by flexible finger 28 also contacting with ring 27 when the button 24 is pressed. The buzzer, or sounding signal 21, is connected by an independent circuit to the same source of electric current through contacts 30 and 31, contactor 31 being 55 connected electrically to finger 25 by flexible connection 32.

As shown also in Fig. 3, the button 24 by means of which these signals 14, 21, 22 and 23 are operated is adapted to be manually pressed far 60 enough to engage the contacts 30 and 31 operating the buzzer signal 21, but, due to the conical form of one of the insulating members 33 on the button 24, the button 24 when released springs back slightly to the position shown in the figure. In this position of the manually pressed 65

button 24 the two lights 14 within the dome 20 shown in Figs. 1 and 2, are maintained lighted and also the supplemental signal lights 22 and 23. The buzzer, however, becomes disconnected as soon as the contactors 30 and 31 are separated. Upon initial pressing of the button 24 5 to operate the buzzer 21 by contactors the lights 14, 22 and 23 are momentarily flashed on as the ring 27 is forced past the ends of fingers 25, 26, 28 and 29. With the contacts 30 and 31 in engagement with each other the fingers are out of contact with the ring 27 so that so long as the button 24 is held down the lights 14, 22 and 23 are not lighted. As soon as the button 24 is released and allowed to return to the position indicated in Fig. 3 the lights 14, 22 and 23 are 10 maintained lighted. 15

I claim:

1. A signal lamp comprising a wall plate, a partition mounted on said wall plate at substantially right angles thereto, a pair of bulbs connected in parallel so as to be normally energized at the same time, one bulb being mounted on the wall plate on each side of said partition, an arched glass cover secured to the wall plate, 20 all portions of said cover being adapted to give the same signal indication when illuminated, said partition being formed to co-act with the cover so that its outer edge is maintained substantially flush with the inner edge of the 25 cover, whereby all portions of said cover are substantially uniformly illuminated when both bulbs are energized and the portion of the cover to one side of the partition would be substantially dark if the bulb therein fails to light, 30 thereby indicating the need for a new bulb.

2. A signal lamp comprising a housing having an opening therein, a light transmitting cover for said opening, all portions of which are adapted to give the same signal indication when illuminated partitioning means in said housing dividing the same into a plurality of compartments, and a source of light in each of said compartments, all of said lights being connected in parallel and adapted to be normally simultaneously energized to transmit light rays through substantially all portions of said cover for giving a single signal indication when all of said lights are energized, a portion of said cover being darkened upon the failure of any of said lights. 40 45

3. A signal light comprising a casing having an opening, a light transmitting closure in said opening having a signalling area, all portions of said area giving a single signal indication when illuminated, a plurality of electric light sources 50 connected in parallel for normally illuminating all portions of the area, and partitioning means within the casing cooperating with said light sources for changing the illumination of a portion of said signalling area on the extinction of 55 either of said light sources to give an indication of such extinction.

4. A signal lamp comprising an enclosure including a light transmitting portion having a signal area, all portions of said area giving the same signal indication when illuminated, a partition mounted in said enclosure, and an electric light source on each side of said partition, said sources being connected in parallel to be normally energized together whereby all portions 60 of said area are normally illuminated to give a signal indication and only a portion of said area is illuminated when one of said light sources fails, to give an indication of said failure. 65 70
